MIXTURE-CONTROLLING MEANS FOR MOTORS.

1,102,341.

Specification of Letters Patent.

Patented July 7, 1914.

Application filed August 4, 1910. Serial No. 575,446.

To all whom it may concern:

Be it known that I, ALEXANDER T. KASLEY, a citizen of the United States, and a resident of Swissvale, in the county of Allegheny and State of Pennsylvania, have made a new and useful Invention in Mixture-Controlling Means for Motors, of which the following is a specification.

This invention relates to explosion motors in which the charge consists of a mixture of air and some suitable combustible, as for example, gas.

An object of the invention is to vary the proportions of air and gas in accordance with the change in quality of the gas. For example, if the gas is rich a larger proportion of air may be mixed with it than if it is lean.

Another object of the invention is to provide means external to the primary or main engine or engines for controlling the mixture which said engine or engines is to use. It has been found that the heat value of gas, one of the component elements of an explosion mixture, is liable to vary and if measured charges of air and gas are introduced into the combustion chamber of the engine, the explosion impulses of the motor are liable to vary in accordance with the change in the mixture due to the change in the quality of gas. For example, during a given period there is liable to be a wide variation of the quality of gas generated by a gas producer. When the producer is first started the gas will not be so rich as it is after the producer has been running for some time. There are other conditions confronted in actual practice which cause a variation in the quality of the gas during a given period but these need not be considered here. It will be apparent then that if the same proportions of air and gas were measured into the gas engine when the gas producer was first started, after the producer had been running for several hours the mixture would be greatly enriched, therefore there would be a variation in the power of the motor due to this cause unless the mixing valve was manipulated to decrease the proportion of gas and increase the proportion of air. To overcome the disadvantages heretofore enumerated, I have provided means whereby the change in the quality of gas will automatically effect a

change in the port areas of the ports or valves communicating with the combustion chamber or mixing valve of the primary engine.

A convenient physical embodiment of my invention may consist of a pilot engine of relatively low capacity and relatively high speed, operating under constant load and controlling mechanism which will vary the proportions of air and gas admitted to the primary engine of relatively large capacity and relatively low rotative speed. The speed responsive device or governor of the pilot engine may be connected through suitable mechanism to an oil relay which actuates the mixing valve of the primary engine as well as the mixing valve of the pilot engine. The mixing valves of the primary engine and the pilot engine are connected by suitable means so that any change in the quality of the gas is transmitted through the speed responsive device to the oil relay, then to both mixing valves. Inasmuch as the pilot engine is designed to have a higher speed than the primary engine it will respond more quickly to changes in gas value and control the port areas leading to the primary engine or engines so that the speed of the primary engine will not appreciably change due to the variations of the gas value because the pilot engine will be sensitive enough and act quick enough to change the port areas for the primary engine or engines before any appreciable change in speed may take place. The pilot engine need necessarily only be large enough to operate the oil relay and move the mixing valve of the primary engine or engines.

In the drawings: Figure 1 is a longitudinal elevational view of my invention; Fig. 2 is a longitudinal elevational view, the mixing chamber of the pilot engine and the oil relay being shown in section, and Fig. 3 is a sectional view on the line 3-3 of Fig. 2.

4 indicates a pilot engine, (preferably a high speed engine) and 5, a power engine, (preferably a low speed engine) whose mixture is to be regulated to suit the quality of the gas. The pilot engine is to carry an approximately constant load and is provided with the usual air and gas valves 6 and 7. In the present instance the air valve 6 is shown as being adapted to be manually

justed so as to be caused to assume a fixed position and provide a constant air port area while the gas inlet port area may be varied by the speed responsive device 8 on the shaft 9. A lever 10 is fulcrumed to a bracket 11 and is engaged by the collar 12 of the speed responsive device, one end of said lever having connection with a link 13 in pivotal connection with a swinging or rocking lever 14 connected to the valve 7. The drive shaft 15 of the motor 4 is provided with a pulley 16 driving the shaft 17 of an air compressor 18 by means of a belt 19, said air compressor supplying compressed air to a starting tank 20 through a pipe 21. If desired, the shaft 15 may drive an ignition magneto 22 through a belt 23. The magneto and air compressor are arranged to provide a constant load for the engine 4, as will also an oil pump.

24 is an oil pump driven by the engine 4 and maintains pressure in the pipe 25 leading to the oil relay 26 from which oil exhausts back to the pump 24 through the pipe 27 and its branch 28. Between the pipes 25 and 27 is a safety valve 29 which unseats when there is undue pressure in the pipe 25 and permits the oil to circulate without entering the relay 26. The oil relay 26 is shown as consisting of a cylinder 30 provided with an inlet 31 whose port area may be controlled by a balanced sliding valve 32 (having pistons 32^a and 32^b) in the chamber in communication with the pipe 25 and with the pipe 27 and its branch 28 the branch 28 taking care of leakage past the piston 32^a. Within the cylinder 30 is a piston 34 provided with a spring 35 interposed between it and one end of the cylinder 30. A pipe 36 leads from the cylinder 30 to a pressure cylinder 37 in which is a piston 38 the stem of which is connected to a rotary mixing valve 39 for the motor 5. This valve is provided with air and gas ports, the port opening designated by the reference numeral 40 being for air and the one designated 41 being for gas. A spring 42 in the cylinder 37 tends to move the piston in one direction which spring may be opposed by pressure from the cylinder 30.

43 is a leakage pipe connecting the cylinder 37 and the pipe 27 to remove oil that leaks past piston 38. Connected to the stem 44 of the valve 32 is a link 45 pivoted to a bracket on the engine 4. Connected to the stem 47 of the piston 34 is a lever 48 fastened to the lever 14 through the medium of a link 49, said lever 48 being also connected to the link 45 through a link 50.

51 is a pressure indicator.

So long as the gas is of constant quality the load on the pilot engine being nearly constant the valve 7 will remain stationary but as soon as the gas varies in quality, as for example, if it becomes impoverished, the

mean pressures in the cylinder will not be great enough to maintain the speed and the valve 7 will be opened by the speed responsive device to permit the requisite number of B. T. U's. to enter through the gas port so as to supply the pilot engine with enough energy to carry the load. It will therefore be apparent that the opening of the valve 7 will be approximately inversely proportional to the quality of the gas. The shifting of the valve 7 will be simultaneous with the shifting of the link 49 so as to move the lever 45 and, by means of it, the relay valve 32, causing it to move to the left to open the port 31 and allowing oil pressure in the cylinder 30 and the pipe 36 to fall. The spring 35 will then move the piston 34 to the right until the relay valve 32 is moved back over the port so as to cause the piston 34 to come to a position of rest. The decrease of pressure in pipe 36 will move the needle of the pressure gage 51 giving the operator notice that the quality of his gas has changed and at the same time the spring 42 will move the piston 37 to the left and thereby operate the valve 39 so as to reduce the air port area for the engine 5 and increase the gas port area. If the spring is made of the proper scale the change of proportions of gas and air will be approximately in proportion to the opening of the valve 7; hence the mixture will be maintained approximately correct for a given quality of gas. If the gas becomes richer, the speed responsive device 8 will close or partially close the valve 7 and through the mechanism just described the relay valve 32 will move to the right and pressure will pile up in the cylinder 30 so as to move the piston 34 to the left and the increased pressure in the pipe 36 will move the piston in the cylinder 37 to the right so as to increase the air port area and decrease the gas port area of the engine 5.

From the foregoing it will be apparent that by the use of the auxiliary or pilot gas engine provided with an approximate constant load, an efficient means is provided for controlling the mixture adjusting mechanism for the larger unit or units, it being obvious that there may be any number of engines 5 operated from the rod connected to the gas valves 39.

Having thus described my invention, what I claim and desire to secure by Letters Patent is:

1. The combination of a plurality of internal combustion engines supplied from a common source and one of which operates under a substantially constant load, of means operated upon the variation of speed of the constant load engine to vary the position of the fuel valve of another engine.

2. A mixture controlling device for low speed internal combustion engines compris-

ing a high speed internal combustion engine, a speed responsive device for the high speed engine, an oil relay actuating means controlled by the said speed responsive device, an oil relay operated thereby, and a low speed engine mixture device controlled by the relay to vary the mixture of the charge to the low speed engine.

3. The combination with a low speed combustion engine, a high speed pilot engine operating under a constant load and means operated by the pilot engine upon variations in speed of said pilot engine for varying the mixture of the charge to the low speed engine.

4. The combination with a plurality of engines, one of which is a governing engine, the governing engine consisting of a high speed engine operating under constant load, a mixture valve for each of the engines other than the governing engine and mechanism operated by the change of speed of the governing engine, due to variation in the quality of gas and for varying the position of the mixing valve so as to vary the port areas of said mixing valve.

5. The combination of a combustion engine having a mixing valve, a fluid actuated device for changing the position of said mixing valve to vary the port areas thereof and means controlling the pressure for said device comprising a high speed engine working under constant load.

6. The combination of a plurality of in-

ternal combustion engines supplied from a common source, one of which operates under variable load and the other of which operates under substantially constant load, of means operated upon variation of speed of the constant load engine to vary the position of the fuel valve of another engine.

7. The combination with a variable load combustion engine, a pilot engine operated under a constant load, and means operated by the pilot engine upon variations in speed of the pilot engine for varying the mixture of the charge to the variable load engine.

8. The combination of a combustion engine having a mixing valve, a fluid actuated device for changing the position of said mixing valve to vary the port areas thereof, and means controlling the pressure for said device comprising an engine working under constant load.

9. The combination of two engines, one of which operates at a higher speed than the other, the higher speed engine working under constant load, and means operated by said constant load engine for varying the mixture of the charge to the other engine.

In testimony whereof, I have hereunto subscribed my name this 2nd day of August, 1910.

ALEXANDER T. KASLEY.
